UNITED STATES PATENT OFFICE.

JOHN WILLIAM McGRATH, JR., OF BROOKHAVEN, MISSISSIPPI.

SOUND POST.

1,408,707.

Specification of Letters Patent. Patented Mar. 7, 1922.

Application filed November 6, 1920. Serial No. 422,221.

To all whom it may concern:

Be it known that I, JOHN W. McGRATH, Jr., a citizen of the United States, and resident of Brookhaven, in the county of Lincoln and State of Mississippi, have invented a new and Improved Sound Post, of which the following is a full, clear, and exact description.

My invention relates to a sound post and aims to provide new and useful improvements in connection with a device of this character.

In this connection it is aimed to provide a sound post which will, as in the case of the prior application, enhance the resonancy of the tone of the instrument in that the vibration of the bass bar will be continued by means of the same for a much longer period.

20 An object of this invention is to provide a sound post which will serve to permit of more vibration being imparted to the essential parts of the instrument.

25 A further object of my invention is the construction of a sound post or instrument attachment, which will give the proper quality of vibration, in that a vibration results when the tone is produced, which will be carried over a greater period than has heretofore been possible.

Reference is had to the attached sheet of drawings, as illustrating one practical embodiment of my invention, and in which—

35 Figure 1 shows one practical embodiment of my invention, in that the attachment is shown associated with a violin, the latter being illustrated in cross section.

Figure 2 is an enlarged side view of the attachment, and

40 Figure 3 is an end view thereof.

In these views the reference numeral 5 indicates the hollow body of the instrument, which in the form illustrated is provided with a bridge 6, a sound post embodying 45 my improved attachment, being interposed between the back and belly of the instrument.

Referring now more particularly to Figures 2 and 3, it will be seen that I provide 50 a sound post, including sections 7 and 8, which may be of any desirable material, the outer ends of which contact with the inner faces of the back and belly of the instrument, the inner ends of these sections 55 being spaced one from the other, as has been clearly indicated.

Now with a view of providing means which will produce improved tonal quality, a spring 9 is interposed between the spaced inner ends of the sound post sections 7 and 8. In the form illustrated the spring is shown as substantially U shaped, which is to be preferred, and it will be noted that the sound post sections contact with the same substantially adjacent its ends. 60 65

It will be appreciated that any vibration imparted to one of the strings will be transmitted to the body of the instrument, and thence to the sound post section 7, and by means of the spring, the vibration set up 70 will pass into the section 8, and so be communicated to the opposite section of the body of the instrument.

To now also incorporate means which will serve to lengthen the vibratory period, it is 75 to be noted that the ends of the spring 9, in the embodiment illustrated, are extended, as has been indicated by the reference numeral 10. The outer ends of these extended portions may conveniently project rearwardly 80 and mount weighted portions 11.

It will be obvious that upon the post sections 7 and 8 being vibrated in the manner specified, that this vibration will be transmitted by virtue of the extended portions 85 10 of the attachment to the weights 11, which will serve to enhance its vibratory effect.

Thus I have provided an attachment in the nature of a sound post, which will embody improved construction over prior devices in that the resilient qualities of the sound post will be enhanced thus allowing more vibration. It will also be understood that by virtue of the weighted portions 11, mounted upon the extended portions 10, 95 that the vibrations will be apparent over a longer period, thus "forcing" the same.

Obviously numerous modifications of structure might readily be resorted to without in the least departing from the spirit of my 100 invention. I claim as my invention—

1. A sound post, including a pair of body portions, having their inner ends spaced from each other, and resilient means interposed and engaging said inner ends, and 105 weights attached to said resilient means.

2. A sound post, including a pair of sections having their inner ends spaced from one another, a spring interposed between and engaging the inner ends of said sections, extended portions attached to the ends of said springs, and weighted portions se- 110

cured to the outer ends of said extended portions.

3. A sound post, including a pair of sections having their inner ends spaced one from the other, a U shaped spring, the inner ends of said sections engaging and being attached to the spring adjacent the ends of the same, extended portions projecting beyond the ends of said spring and weighted portions secured to the outer ends of said extended portions.

4. A sound post, including a pair of sections having their inner ends spaced one from the other, a U shaped spring, the inner ends of said sections engaging and being attached to the spring adjacent the ends of the same, extended portions projecting beyond the ends of said spring, the outer ends of said extended portions being bent rearwardly, and weighted portions secured to such outer ends. 15
